JOHN H. SHAW, OF NEW HAVEN, CONNECTICUT, ASSIGNOR TO SARGENT & COMPANY, OF NEW HAVEN, CONNECTICUT, A CORPORATION OF CONNECTICUT.

DIPPING MECHANISM FOR ELECTROPLATING APPARATUS.

963,817.

Specification of Letters Patent. Patented July 12, 1910.

Application filed May 3, 1909. Serial No. 493,576.

To all whom it may concern:

Be it known that I, JOHN H. SHAW, of the city and county of New Haven and State of Connecticut, have invented new and 5 useful Improvements in Dipping Mechanism for Electroplating or Similar Apparatus, of which the following is a full, clear, and exact description, when taken in connection with the accompanying drawings, 10 which form a part hereof.

This invention has for its object the production of a simple and efficient apparatus for continuously carrying on the operation of electro-plating by providing mechanism 15 for automatically immersing and extracting the articles to be electro-plated and transferring them from one bath to the other. This object is accomplished by means of a traveler supporting the carrier from the 20 work holder, and novel mechanism for actuating the carrier at the proper time to raise the work holder to remove the articles from one bath and immerse or dip them again in the next succeeding bath. Hitherto the 25 means provided for raising and lowering the work holder have failed to give the articles the full benefit of the bath, because the articles have been gradually raised from and lowered into the bath as they have traveled 30 from one end of the tub to the other.

The present invention provides a rotary member that actuates the carrier to swing the work holder in a reverse direction from the movement of the traveler as the work 35 holder is raised or lowered, thereby permitting the articles or work holder to travel on the same horizontal plane substantially the full length of the bath.

In addition the present invention consists 40 of the other improvements and combinations of parts set forth and claimed hereinafter.

Referring to the drawings for a more specific description of the apparatus, Figure 1 represents a plan view of a portion of the 45 apparatus, Fig. 2, a side elevation of a portion of the apparatus, and Fig. 3, a transverse vertical section through the traveler and carrier and the actuating mechanism.

In all figures, similar letters of reference 50 represent like parts.

In the drawings, the parts designated by the letters A, A' represent a series of baths or tubs, and B an endless chain rotated in a horizontal plane by means of a sprocket C 55 driven by any suitable actuating mechanism

(not herein shown). Suspended from links X of the chain properly spaced are travelers D. These may be suspended (as shown more particularly in Fig. 3) by means of a supporting plate T fitting over the link X 60 of the chain and secured to the upper end of the traveler D by a bolt or bolts V. Each traveler D has transverse bearings for a loosely rotating shaft or carrier E to an outer end of which is rigidly secured a supporting arm F with a holder F'. On either side of the traveler D wheels G are loosely mounted on the carrier E. These wheels G are adapted to run on the elevated track J mounted below the chain B and above the 70 tank or tanks A, A', etc. The track is herein shown consisting of two parallel rails J and J', and the wheels of the carrier are held on the rails by means of a depending stud H on which is mounted a roller I of 75 proper width to fit between the two rails of the tracks J and J' and prevent lateral movement of the traveler D. There is also mounted on the carrier or shaft E one or more gears L and M which are secured to 80 the shaft E by keys N, or other suitable means so that they will rotate with the shaft E, although capable of a limited longitudinal movement thereon. These gears L and M are adapted to engage ratchets O and P, 85 respectively, which are located in proximity to the rails J and J' of the elevated track. The ratchets O and P are situated (as shown more particularly in Figs. 1 and 2) over the partitions S, S', between the several tubs 90 or baths A, A', etc. Work-holders R are adapted to be supported on the holder F' of the arm F of the carrier in any suitable manner.

The operation of the apparatus is as follows: The articles to be plated are placed upon work holders R, and the chain B set in motion by means of the sprocket C. When one of the travelers D moving along the track J, J' comes to a point where one 100 of the gears L or M engages one of the ratchets O or P, the teeth of the gear will mesh with the teeth of the ratchet so that the gear will be rotated in the direction indicated by the arrow (Fig. 2) and the carrier E to 105 which the gear is keyed will rotate therewith swinging the arm F around so that its end to which the work holder is secured describes a curve substantially like that indicated in dotted line (Fig. 2). This move- 110

ment of the outer end of the arm F tends to raise the work holder out of one of the tubs, over the partition S', and dip it into the next succeeding tub or bath near its end 5 partition S. The continued movement of the chain and the depending carrier moves the work holder forward on the same horizontal plane through the bath or tub A, until one of the gears L or M engages the next 10 succeeding ratchet mounted over the partition S² at the other end of the bath or tub A, when the operation of raising the work holder will be repeated as above described.

By this construction the work holder is 15 carried forward by the endless chain until it comes to a position almost against the partition S' or S². When it is raised by the rotation of the axle the outer end of the arm tends to swing slightly backward away from 20 the partition, and in the reverse direction from that of the movement of the traveler D, as indicated by the dotted lines (Fig. 2). On the other hand, when the work holder is again dipped in the succeeding tub the complete revolution of the axle and the arm 25 tends to move the work holder backward into close juxtaposition with the partition S of the next succeeding bath or tub A, so that the work holder practically travels through 30 the full length of the tub on substantially the same horizontal line.

As it may be desired to raise or dip certain classes of articles more rapidly than others, the two gears L and M mounted on 35 the axle E of the carrier differ in diameter. By this arrangement, when the gear L is in operation the rotation of the shaft E will take longer than when the gear M is in operation. As the gears L and M are capable 40 of a limited longitudinal movement on the shaft E, either one may be moved on the axle to or from engagement with its corresponding ratchet O or P on the tracks J and J'.

45 Having now described my invention, which may vary in its detail without departing from the spirit thereof, what I claim and desire to secure by Letters Patent, is:—

1. In dipping mechanism, the combination 50 with a work holder; of a traveling rotary member adapted to raise or lower it upon the rotation of said member, substantially as described.

2. In dipping mechanism, the combination 55 with a work holder; of a rotary member adapted to travel horizontally above a bath, and upon its rotation to raise or lower the work holder from or into the bath, substantially as described.

60 3. In dipping mechanism, the combination with a rotary member adapted to travel above a bath and to be intermittently rotated; of a work holder raised or lowered upon the rotation of said member, substantially as described.

4. In dipping mechanism, the combination with a work holder; of a traveling carrier; a rotary member carried thereby, and adapted to raise or lower the work holder upon the rotation of said member, substantially as described. 70

5. In dipping mechanism, the combination with a series of work holders; of a series of rotary members adapted to raise or lower them upon the rotation of said members; and means for propelling said members horizontally and for rotating each member separately, substantially as described. 75

6. In dipping mechanism, the combination with a carrier; of a work holder supported thereby; and means for rotating said carrier and thereby raising or lowering said holder, substantially as described. 80

7. In dipping mechanism, the combination with an endless chain; of a carrier propelled thereby; a work holder supported by said carrier; and means for rotating said carrier and thereby raising or lowering said holder, substantially as described. 85

8. In dipping mechanism, the combination with a track; of a carrier adapted to travel thereon; a work holder supported thereby; and means for rotating said carrier and thereby raising or lowering said holder, substantially as described. 90

9. In dipping mechanism, the combination with a carrier capable of rotation; a work holder supported thereby; and means for rotating said carrier to raise or lower 100 said holder, substantially as described.

10. In dipping mechanism, the combination with an endless chain; of a carrier propelled thereby and capable of rotation; a work holder supported thereby; and means 105 for intermittently rotating said carrier, substantially as described.

11. In dipping mechanism, the combination with an endless chain; of a series of carriers propelled thereby and capable of independent rotation; work holders supported by said carriers; and means for rotating said carriers separately to raise or lower 110 said work holders, substantially as described. 115

12. In dipping mechanism, the combination with a rotary carrier; a crank arm rigidly connected therewith for supporting the work holder; and means for rotating said carrier and crank arm, substantially as described. 120

13. In dipping mechanism, the combination with an endless chain; of a series of carriers propelled thereby; work holders supported by said carriers; a gear mounted on 125 said carrier and adapted to rotate therewith; and an engagement adapted to rotate said gear, substantially as described.

14. In dipping mechanism, the combination with an endless chain; of a traveler 130

mounted thereon; a rotary shaft loosely mounted on said traveler having a crank arm; a gear and ratchet connection with said shaft to rotate the same; and a work holder supported by said crank arm and raised or lowered upon the rotation of said shaft, substantially as described.

In witness whereof, I have hereunto set my hand on the 27th day of April, 1909.

JOHN H. SHAW.
